(57) **CLAIM**

The ornamental design for an iron caddy as shown and described.

DESCRIPTION

FIG. 1 is a front perspective view of the design of the iron caddy of the present invention;

FIG. 2 is a top plan view of the iron caddy shown in FIG. 1;

FIG. 3 a front elevation view of the iron caddy shown in FIG. 1;

FIG. 4 is a right elevation view of the iron caddy shown in FIG. 1;

FIG. 5 is a left elevation view of the iron caddy shown in FIG. 1.

FIG. 6 is a rear elevation view of the design of the iron caddy shown in FIG. 1.

FIG. 7 is a bottom plan view of the iron caddy shown in FIG. 1.

FIG. 8 is a front perspective view of the iron caddy shown in FIG. 1, carrying an iron and an ironing board; and, FIG. 9 is a front perspective of the iron caddy shown in FIG. 1, including an optional accessory holder.

Any broken line depictions illustrate environmental structure and form no part of the claimed design. Any shading and cross-hatching are likewise not features of the design but are used to illustrate surface contours of the illustrated design.

1 Claim, 6 Drawing Sheets
